UNITED STATES PATENT OFFICE.

ALEXANDER ETTINGER, OF CLEVELAND, OHIO.

DEVICE FOR MEASURING KEYS.

1,250,999.

Specification of Letters Patent. Patented Dec. 25, 1917.

Application filed January 31, 1916. Serial No. 75,246.

To all whom it may concern:

Be it known that I, ALEXANDER ETTINGER, a citizen of the United States, residing at Cleveland, in the county of Cuyahoga and 5 State of Ohio, have invented certain new and useful Improvements in Devices for Measuring Keys, of which the following is a specification.

This invention relates to a device for measuring pin tumbler lock keys of the Yale type, and has for its main object to provide means for quickly registering the number and depth of the notches in such a key. The purpose of thus registering the notches being 10 to give a record of a key, so that a locksmith can make a duplicate key without removing the lock or without depriving the owner of the use of the original key for a pattern. Also to enable a locksmith to make 15 a key from a record for a certain lock in case the key is lost.

With the above and other objects in view as will be understood, the invention will be hereinafter fully described in connection with the 20 accompanying drawings, which illustrate a preferred embodiment thereof, and the novel features of the invention will be distinctly pointed out in the appended claims.

In the drawings like characters of reference indicate corresponding parts.

Figure 1 is a side elevation of a key measuring device constructed in accordance with my invention,

Fig. 2 is an end view of Fig. 1,

Fig. 3 is a plan sectional view taken on line 3—3 of Fig. 1,

Fig. 4 is a cross sectional view, on an enlarged scale, with the key in place, taken on line 4—4 of Fig. 1,

Fig. 5 is a longitudinal section taken on line 5—5 of Fig. 4, and

Fig. 6 is a perspective view of one of the plungers.

Referring to the drawings, 1 represents a base having at its rear end an upright bracket 2, from which project a pair of forwardly extending lugs 3 for supporting a pivot pin 4. A plurality of indicating fingers 5 are pivotally supported on said pivot 45 pin preferably with spacing washers therebetween, and their free forward ends 6 are adapted to project through and move in vertical slots 7 of a register plate 8 curved on the arc of a circle, with said pivot point as 50 a center. Said register plate is fixed to the front end of the base by screws 8', and its

upper end rests upon and is connected at 9 to a top-piece 10, formed integrally with a pair of spaced uprights 11, which are fastened to the sides of said base. Series of 60 marks and numerals on the register plate, as illustrated at 12, serve the purpose of scales for the reading of the limit of the movement of the indicating fingers in measuring a key. In order to show just where the free projecting ends of the indicating fingers stop when measuring a key, beads 13 are slidably mounted upon guide wires 14, which are arranged parallel to the slots 7 of the register plate. These guide wires are held snugly 65 against the face of the register plate and are adapted to cause the beads to frictionally engage the same for holding them in a set position. The upper ends of the guide wires pass through apertures 15 in the register 70 plate and knots 16 tied thereat, and their other ends pass through similar apertures 17 in the register plate just above the top of the base. The free ends of said guide wires enter longitudinal openings 18 in a raised 75 cross-bar 19 of the base, and are securely held therein by binding screws 20. The guide wires are drawn tight to obtain the proper tension for holding the beads in a set position by means of tightening screws 80 21, which are mounted in the base and are adapted to bear against the guide wires.

Arranged crosswise of the base adjacent the upright bracket 2 is a block or holder 90 22, having a longitudinally extending head 23, which is provided with a longitudinal recess 24, and suitably spaced cross slots 25 for accommodating and guiding the indicating fingers 5. The holder 22 is removably mounted upon the base. It is centered by 95 means of pins 26 and held in place against the upright bracket by a locking screw 27, which passes through the bracket and screws into the holder. Said holder is provided with a cylindrical socket 28 for receiving a bushing 29, which in turn is adapted to receive an ordinary plug of a lock of the Yale type, such as indicated at 30. Said plug is constructed with a suitable key-way 31 for a key 32, and in the wall of the plug above 100 the key hole is a plurality of vertical holes 33 for accommodating the usual pin tumblers in said class of locks. The bushing 29 is cut away at 34 to provide a longitudinal opening above the row of holes 33, and 105 through the wall 35 of the holder, in vertical alinement with said holes and the cross

slots 25, are square holes 36. Plungers consisting of an elongated square head 37 and a round stem 38 are slidably mounted in the holes 36 and 33, and the pointed ends 39 of their stems are adapted to be engaged by the key 32 for forcing the plungers upwardly to actuate the indicating fingers 5, which rest upon the upper ends of the plungers. The tops of the square heads of the plungers 10 are rounded as at 40 for giving a smooth cam action to the indicating fingers. Said plungers are prevented from falling below a certain point, when the key is not in the plug of the lock, by means of cross pins 41, which 15 are fixed in the heads thereof and are adapted to rest upon the bottoms of the cross slots 25. The plug 30 is held in proper position to bring the holes 33 directly under the indicating fingers 5 by the use of a centering 20 screw 42, which is threaded in the holder and passes through an opening in the bushing 29 and engages a shallow recess 43 in said plug.

The reason for making the holder 22 removable is to be able to substitute therefor another holder having a different number of cross slots 25 or the same number differently spaced, which will correspond with the pin tumblers of the locks to be measured.

30 In order to measure a key with this invention, it is necessary to first select a plug such as 30, which corresponds with the plug of the lock to be measured. This plug is inserted into the bushing 29 having the 35 proper number and spacing of cross slots 25, and the bushing placed in the holder 22. The centering screw 42 is then turned to engage the recess 43 in the plug. The stems 38 of the plungers are inserted in the holes 33 of the plug and the indicating fingers 5 are arranged in the cross slots 25. The plungers are supported by their cross pins 41 engaging the bottoms of said cross slots, and said indicating fingers rest upon the 45 heads of the plungers. The key to be measured, as for instance 32, is inserted into the key-way of the plug 30, and its notches of varying depths will engage the pointed ends 39 of the plungers thereby forcing them upwardly, and thus actuating the indicating fingers according to the depths of the corresponding notches. By sliding the beads 13 upon the guide wires 14 until their upper edges are brought even with the upper edges 55 of the indicating fingers, the limit of movement of the indicating fingers is conveniently registered. When the key is removed, the indicating fingers return to their original positions. A new key may then be made 60 from a blank, by fitting it into the key-way of the plug and filing the notches thereof until it causes the indicating fingers to move to the positions registered by the beads. Or from the positions of the beads with relation to the marks and number 12 on the

register plate, a record may be taken, and a key afterward made by setting the beads according to the record and proceeding as already explained.

By constructing the holder so that it is 70 removably fixed to the base and is interchangeable, and providing the same with a plurality of bushings adapted to receive various sizes of plugs, the device is efficient for measuring keys for all styles of pin tumbler locks. Although the device set forth and described is only capable of measuring a key having three notches, it will be understood that the same principle is applicable for measuring keys having a greater 75 number, and also that slight changes in the details of construction may be made within the scope of the claims.

Having fully described my invention, what I claim is:

1. In a key measuring device, the combination of a base, indicating fingers pivoted to the base, a holder removably supported by the base, a removable bushing carried by the holder, a plug of a pin tumbler lock in 90 the bushing, and means actuated by a key inserted into said plug for operating the indicating fingers, substantially as described.

2. In a key measuring device, the combination of a base, indicating fingers pivoted to the base, a holder removably supported by the base, a plug of a pin tumbler lock carried by the holder, the plug being provided with pin holes, the holder being slotted for receiving the indicating fingers, and 100 plungers slidably mounted in the holder in vertical alinement with the slots and extending into the pin holes of said plug, substantially as described.

3. In a key measuring device, the combination of a base, indicating fingers pivoted to the base, a holder supported by the base, a plug of a pin tumbler lock carried by the holder, the plug being provided with pin holes, the holder being slotted for receiving the indicating fingers, plungers slidably mounted in the holder in vertical alinement with the slots and extending into the pin 110 holes of said plug, and cross-pins fixed in the plungers adapted to rest upon the bottoms of said slots for supporting them in normal position, substantially as described.

4. In a key measuring device, the combination of a base, an upright bracket at the rear end of the base, lugs extending forwardly from the bracket, a pivot pin carried by said lugs, indicating fingers connected to the pivot pin, a holder, a locking screw for removably fixing the holder to said bracket, a plug of a pin tumbler lock carried by the holder, the plug being provided with pin holes and means actuated by a key inserted into said plug for operating the indicating fingers, substantially as described.

5. In a key measuring device, the combi-

- nation of a base, indicating fingers pivoted to the base, a plug of a pin tumbler lock supported by the base, means actuated by a key inserted into said plug for operating 5 the indicating fingers, a register plate fixed to the base, the register plate being provided with slots for receiving the free ends of the indicating fingers, guide wires arranged on the register plate, and beads slidably 10 mounted upon the guide wires adapted to be set to the limit of movement of the indicating fingers, substantially as described.
6. In a key measuring device, the combination of a base, indicating fingers pivoted 15 to the base, a plug of a pin tumbler lock supported by the base, means actuated by a key inserted into said plug for operating the indicating fingers, a register plate fixed to the base, the register plate being provided with slots for receiving the free ends 20 of the indicating fingers, guide wires arranged on the register plate, beads slidably mounted upon the guide wires, and means for tightening the guide wires to draw them close to the register plate for causing the 25 beads to frictionally engage the register plate, substantially as described.

In testimony whereof I affix my signature.

ALEXANDER ETTINGER.
